UNITED STATES PATENT OFFICE.

HARRY S. DICKINSON, OF MOLINE, ILLINOIS, ASSIGNOR TO THE DUNHAM COMPANY,
OF BEREA, OHIO, A CORPORATION OF OHIO.

DOUBLE-ROLLER PULVERIZER.

Application filed January 8, 1927. Serial No. 159,782.

This invention relates to double roller pulverizers of the general type disclosed in the Dunham Reissue Letters Patent No. 13,921, dated June 1, 1915, and the object of the present invention is to overcome certain difficulties inherent in the operation of a double roller pulverizer of the character shown in the said Dunham patent, and particularly to utilize the draft strains developed during the travel of the implement in such a way as to better accommodate the implement to the conditions encountered in rough ground.

The implement of the Dunham reissue patent is one which employs rocking frames as mountings for the front and rear disk axles, with pivotal connections for the rocking frames located above the line between the front and rear axles. This elevated location of the pivot point brings the draft line normally at a point above the front axle, so that in operation on substantially level ground, the draft strain will bear more heavily upon the front rank of roller disks which is desirable in normal operation in order to utilize the draft strains most advantageously in crushing down ground inequalities encountered by the front rank. However, if the front rank of roller disks drops down into a dead furrow or other depression, the distance of the draft line above the front axle will increase with a resulting increase in the draft thrust on the front rank which becomes a detriment, in that its tendency is to cause the front rank to dig even more deeply into the bottom of the furrow, and in such circumstances it is desirable that the draft be reduced rather than increased in order to better enable the front rank of roller disks to ride up out of the furrow.

The object of the present invention is to provide a connection of such character as to retain a normal draft down thrusting effect on the front rank, while the machine is traveling over level ground, and to avoid the imposition of any increment of the down thrusting draft action when the front rank falls into a furrow and to more effectively utilize the down thrust of the draft when the front rank rides up into a ridge, thereby harmonizing the draft effect to the conditions actually encountered in the field.

In order to better understand the special features of the present invention, it is

proper to state that in roller pulverizers of the approved type, the following characteristics have been developed to secure better harmony both in operation and in manufacture: (1) double sets of rollers, that is front and rear ranks of rollers; (2) larger rollers in front to do the major portion of the crushing; (3) smaller rollers in the rear for secondary pulverizing and smoothing the soil surface; and (4) a draft frame connection to the roller frames so arranged as to distribute a major portion of the dead weight, and also a component of the draft itself to the front rank rollers when in use.

The machine of the Dunham reissue patent conforms to the above conditions, but as pointed out makes no provision for utilizing the draft effect in the most advantageous manner.

Further objects and details of the present invention will appear from a description thereof in connection with the accompanying drawings wherein—

Figure 1 is an end elevation of the present invention operating on level ground.

Fig. 2 is a similar view showing the position assumed by the parts when the front rank rides into a depression;

Fig. 3 is a similar view showing the arrangement of the parts when the front rank rides up on a ridge or elevation; and

Fig. 4 is a fragmental sectional plan view of the connections constituting the present invention.

It will be understood that the construction of the mountings at each end of the roller axles is the same so that a description of one will suffice for both. The draft frame comprises a tongue 10 to the rear end of which are secured front and rear cross rails 11 connected at their ends by depending brackets 12 which converge downwardly and are preferably cored out at the center to reduce the weight. Each bracket frame at its lower end is provided with arcuately disposed rack teeth 13 extending forwardly from the front edge of the lower portion of the bracket. The rear portion of the bracket, behind the rack teeth, is extended to afford a heel 14 which provides a mounting for a link 15 which is pivoted to the heel by a pivot stud 16 or the like, and is pivoted at its forward end by a pin or stud 17 to an ear 18 extending upwardly from the forward end of an equalizer bar 19 which at its forward

end carries the forward roller disk shaft 20, and at its rear end carries the rear roller disk shaft 21.

The equalizer bar is of offset formation comprising a depressed rearwardly extending leg 22 merging at its forward end into a head portion 23, which latter terminates in an upstanding shoulder 24 provided with teeth 25 which are held in mesh with the teeth 13 by the link 15 whose object and purpose is simply to hold the parts in intermeshing relation. The location of the teeth 25 is preferably in advance of the medial line between the front and rear axles, and these teeth are located above the plane of the two axles, and when the parts occupy the normal relation indicated in Fig. 1, the center tooth of the series 25, will mesh with the center recess of the series 13, so that this medial point in the co-acting series of teeth will constitute a point for the application of a draft thrust imparted through the bracket 12 from the point of connection of the tongue 10 with the tractor or other source of draft, as the case may be.

The line of draft will normally lie in an upwardly sloping line substantially as indicated by the dotted lines of Fig. 1, and in these circumstances the down thrusting component of the draft pull, or the lever action thereof as it may be termed, will be in ratio to the vertical distance from the center of the front axle to the draft line. Obviously, in these circumstances, if this distance be increased, when the front rank of disks drops down into a dead furrow, the leverage effect of the draft and the consequent down thrust on the front rank will be increased, which is a condition which the present invention is designed to avoid.

By an inspection of Fig. 2, it will be observed that when the front rank rolls down into a depression, there will be a rocking or rolling of the gear teeth on one another, with the result that the point of application for the draft will now lie at the point of intermeshing between the lowermost teeth of the two series. In these circumstances the draft line will be correspondingly lowered so that the vertical distance between the front axle and the draft line will be actually lessened with the parts proportioned as indicated, and with the attendant result that in these circumstances less than the normal amount of the draft down thrust will be imposed upon the front rank so that a condition will be established most favorable to the lifting and rolling of the front rank out of the depression. This lessening of the draft on the front rank will necessarily redispone the draft in such a way that a larger component of the draft effect will be momentarily imposed upon the rear rank which is desirable in order to cause the rear rank, when elevated as shown in Fig. 2, to

press or scoop down an increased amount of earth to fill up the depression.

Fig. 3 illustrates the disposition of the parts when the front rank is riding up over a ridge, and in these circumstances the intermeshing teeth will be the ones at the upper ends of the two series, so that in this adjustment the draft line will rise with the front rank and maintain or even increase the leverage action in such a way as to impose a greater than normal component of the draft effect upon the front rank, with the result that in these conditions the effective action of the front rank will be increased which is desirable in forcing down or spreading out the ridged up soil and with a corresponding reduction in the pressure of the rear rank, which is equally desirable in the circumstances mentioned.

In maintaining the gear teeth in meshing relation, it is desirable that the linkage shown should be of a somewhat loose character in order that it may not interfere with the proper intermeshing of the gear teeth with one another, or with the readjustment of the parts under the conditions described, although it is obvious that in lieu of the linkage shown, other means might be provided for holding the parts in assembled relation without departing from the spirit of the invention.

It is not deemed necessary to illustrate or describe any of the special means commonly employed in the art for journaling the gang shafts, or for permitting quick detachment of the parts, since such mechanisms are well understood by those skilled in the art, and form no part of the present invention.

Furthermore it is obvious that in carrying out the details of the present invention, the arcuate arrangement and location of the intermeshing teeth can be changed or modified to vary the extent or degree to which the draft effects will be redistributed under operating conditions, and is hence not intended to limit the invention to one in which the draft action will be absolutely reduced when the draft point is lowered, or absolutely increased when it is raised, since any advantageous redistribution of the draft to reduce or minimize the results attending the employment of a fixed pivotal point as a draft center by means of the character herein shown and described is deemed to be equally within the scope of the present invention.

I claim:

1. In an implement of the class described, the combination of a draft frame, a front axle provided with roller elements, a rear axle provided with roller elements, an equalizing connection for carrying the two axles, and engaging rolling elements on the equalizer connection and the draft frame respec-

tively so disposed as to lower the point of engagement with said rolling elements when the front axle is disposed below normal, and to elevate the point of engagement of said rolling elements when the front axle is elevated for redistributing the draft in conformity with the variations in ground conditions, substantially as described.

2. In an implement of the class described, the combination of a draft frame provided at each end with a depending bracket having formed thereon an arcuately configured draft imparting surface, an equalizer frame coacting with each depending bracket, and having formed thereon a suitably configured draft receiving surface in coacting relation with the draft imparting surface, a front axle carried between the forward ends of the equalizer frames and roller elements carried thereby, a rear axle carried between the rear ends of the equalizer frames and roller elements carried thereby, and means for maintaining the draft applying surfaces in coacting relation with one another, the arrangement being such that when the front axle is elevated the point of contact between said surfaces will be correspondingly elevated, and when the front axle is depressed the point of contact will be correspondingly depressed to vary the application of draft effect in conformity with variations of the conditions of the ground, substantially as described.

3. In an implement of the class described, the combination of a draft frame provided at each end with a depending bracket having formed thereon a suitably configured draft imparting surface, an equalizer frame coacting with each depending frame, and having formed thereon a suitably configured draft receiving surface in coacting relation with the draft imparting surface, a front axle carried between the forward ends of the equalizer frames and roller elements carried thereby, a rear axle carried between the rear ends of the equalizer frames and roller elements carried thereby, and a link for each of the equalizer frames pivotally connected at one end to said frame and at the other end to the depending bracket for maintaining the draft applying surfaces in coacting relation, substantially as described.

4. In an implement of the class described, the combination of a draft frame provided at each end with a depending bracket, each of the brackets having formed on its forward edge a series of arcuately disposed gear teeth, an equalizer frame coacting with each of the depending brackets, and having formed thereon a series of rearwardly facing suitably disposed gear teeth meshing with the forwardly facing gear teeth on the bracket, a front axle mounted between the forward ends of the equalizer frames and roller elements carried thereby, a rear axle mounted between the rear ends of the equalizer frames and roller elements carried thereby, and means for holding the gear teeth in meshing relation, the parts being so disposed as to relatively elevate the intermeshing points when the front axle is elevated, and to relatively depress the intermeshing points when the front axle is depressed to vary the draft effect in conformity with variations in the condition of the ground, substantially as described.

5. In an implement of the class described, the combination of a draft frame provided at each end with a depending bracket having formed on its front face a series of suitably disposed forwardly facing gear teeth, an equalizer frame coacting with each bracket and shouldered at a point in advance of its fore and aft center to afford an elevated front portion provided with a series of rearwardly facing teeth in mesh with the forwardly facing teeth on the bracket, a link pivoted at its forward end to the equalizer frame, and at its rear end to the bracket for holding the teeth in meshing relation, a front axle carried between the forward ends of the equalizer frame and roller elements carried thereby, and a rear axle carried by the rear ends of the equalizer frames and roller elements carried thereby, the parts being so related that the point of effective engagement of the teeth will be relatively lifted by the lifting of the front axle and lowered by a lowering of the front axle to redistribute the draft connection in conformity with variations in the ground conditions, substantially as described.

HARRY S. DICKINSON.
